DESIGN FOR A GRIDDLE

Styles T. Howard, Jeffersonville, Ind.

Application June 4, 1941, Serial No. 101,298

Term of patent 3½ years

To all whom it may concern:

Be it known that I, Styles T. Howard, a citizen of the United States, residing in the city of Jeffersonville, in the county of Clark and State of Indiana, have invented a new, original, and ornamental Design for a Griddle, of which the following is a specification, reference being had to the accompanying drawing, forming a part thereof.

Fig. 1 is a top plan view of the griddle showing my new design.

Fig. 2 is a front elevational view thereof; and
Fig. 3 is a perspective view of the same as seen from below.

I claim:

The ornamental design for a griddle, substantially as shown.

STYLES T. HOWARD.
